UNITED STATES PATENT OFFICE.

LOUIS MAISEL, OF BUFFALO, NEW YORK.

DESIGN FOR A TELEPHONE-SUPPORT.

58,794.

Specification for Design.

Patented Aug. 30, 1921.

Application filed January 22, 1920. Serial No. 353,338. Term of patent 14 years.

To all whom it may concern:

Be it known that I, LOUIS MAISEL, a citizen of the United States, residing at Buffalo, in the county of Erie and State of New York, have invented a new, original, and ornamental Design for a Telephone-Support, of which the following is a specification.

In the accompanying drawings:

Figure 1 is a side elevation of a telephone support embodying the design.

Fig. 2 is a perspective view thereof.

I claim:

The ornamental design for a telephone support as shown.

LOUIS MAISEL.
